[57] **CLAIM**

The ornamental design for a light bracket for a fishing pole, as shown and described.

DESCRIPTION

FIG. 1 is an environmental view of the light bracket for a fishing pole showing our new design;

FIG. 2 is an enlarged top plan view thereof;

FIG. 3 is a right hand elevational view thereof;

FIG. 4 is a bottom plan view thereof;

FIG. 5 is a left hand elevational view thereof;

FIG. 6 is a front elevational view thereof; and,

FIG. 7 is a rear elevational view thereof.

The broken line showing of numbers in FIGS. 1, 2, 3, 4, 5, 6, and 7 is for illustrative purposes only and forms no part of the claimed design.

The contrasting shading represents rubber and cloth-like material.
